United States Patent Office

Des. 179,176
Patented Nov. 6, 1956

179,176

PHOTOGRAPHIC FLASHLIGHT APPARATUS

Frank A. Zagara, Rochester, N. Y., assignor to Eastman
Kodak Company, Rochester, N. Y., a corporation of
New Jersey

Application June 8, 1956, Serial No. 41,816

Term of patent 14 years

(Cl. D61—1)

Fig. 1

Fig. 2

Fig. 3

Fig. 4

Fig. 1 is a front elevational view of a photographic flashlight apparatus showing my new design;

Fig. 2 is a side elevational view of the photographic flashlight apparatus shown in Fig. 1;

Fig. 3 is a rear elevational view of the photographic flashlight apparatus shown in the preceding figures; and

Fig. 4 is a fragmentary detailed section taken on line 4-4 of Fig. 3.

I claim:

The ornamental design for a photographic flashlight apparatus, as shown.
